(57) **CLAIM**

The ornamental design for a luggage bow tie, as shown and described.

DESCRIPTION

FIG. 1 is a perspective view of a luggage bow tie embodying the new design;

FIG. 2 is a front view of the luggage bow tie shown in FIG. 1;

FIG. 3 is a back view of the luggage bow tie shown in FIG. 1;

FIG. 4 is a right side view of the luggage bow tie shown in FIG. 1;

FIG. 5 is a left side view of the luggage bow tie shown in FIG. 1;

FIG. 6 is a top view of the luggage bow tie shown in FIGS. 1; and,

FIG. 7 is a bottom view of the luggage bow tie shown in FIG. 1.

The broken lines showing an element on the luggage bow tie are for the purposes of illustrating environment and forms no part of the claimed design.
